BELL RINGING MECHANISM

Ralph A. Light, Cynwyd, and Joseph W. Price, Jr.,
Philadelphia, Pa., assignors to The United
States Metallic Packing Company, Philadel-
phia, Pa., a corporation of Pennsylvania

Application January 5, 1933. Serial No. 650,242

8 Claims. (Cl. 121—2)

This invention relates to mechanism for ringing the bells of locomotives and the like; and it is concerned more particularly with pressure fluid actuated mechanisms for automatically operating bells of the swinging type as distinguished from those of the clapper operated type.

Ringing mechanisms of the kind specifically referred to as heretofore constructed were complicated; expensive to install; difficult of adjustment to prevent complete rotations of the bells with attendant irregularity in the frequencies of the soundings, and, on the other hand, to predetermine a swing of sufficient amplitude which would insure the restoration of the actuating parts to starting position by the bell for repetitions of the operative cycle; and, moreover, susceptible to easy derangement in use.

Our invention is directed in the main toward overcoming the above recited drawbacks; and this desideratum we attain, as hereinafter fully disclosed, through provision of a simple, reliable, and easily attached automatic bell ringing mechanism wherein a fluid-actuated piston on its power strokes coacts alternately with the opposite convexed edges of the radial lobe cam affixed to the axis of the bell to impart swinging movement to the latter first in one direction and then in the other; and wherein a spring-urged buffer stop coacts likewise alternately with the opposite convexed edges of the lobe cam, to prevent complete rotations of the bell, said buffer stop also acting to gradually retard the bell as the latter nears the limits of its movements in opposite directions.

Other objects and attendant advantages of this invention will be manifest from the detailed description following in connection with the attached drawings, wherein Fig. I is a view showing our improved ringing mechanism in association with a typical locomotive bell.

Fig. II is a plan sectional view of the bell ringing mechanism, taken as indicated by the arrows II—II of Fig. I and drawn to a larger scale.

Fig. III is a longitudinal sectional elevation of the mechanism viewed as indicated by the arrows III—III in Figs. I and II.

Fig. IV is a perspective view of a valve comprised in the mechanism; and

Fig. V is a view corresponding to Fig. II with the moving parts of the mechanism differently positioned.

With more detailed reference first more especially to Fig. I of these illustrations, the numeral 10 designates the locomotive bell, which, after common practice, is suspended centrally from a

yoke 11 whereof the trunnions 12 and 13 are journalled in bearings 14, 15 of a double-armed supporting frame 16.

The bell ringing mechanism of our invention is comprehensively indicated by the numeral 17, the same having its moving parts housed within a casing 18 secured to the bearing 14 of the bell frame 16. As shown in Figs. II, III and V, the casing 18 affords a circular chamber 19 in concentric relation to the swinging axis of the bell 10. This circular chamber 19 is closed at one side by a cover plate 20 having an axially projecting boss 21 abutted against the face of the trunnion bearing 14 whereto it is made permanently fast preferably by welding along the line of contact, the casing proper 18 being removably secured to said cover plate 20 after permanent attachment of the latter as just explained, by screw bolts indicated at 22. This method of mounting the mechanism is obviously simple and convenient as well as inexpensive.

Pinned to the bell trunnion 12 within the chamber 19 of the casing 18 is a lobe cam 23 having oppositely convexed side edges 23a, 23b mergent with a concentric portion 23c. During the operation of the mechanism, the oppositely convexed edges 23a, 23b of the cam 23 are acted upon by a ball 24 which is socketed into the head 25a of a screw 25 let axially into the forward end of a piston 26, and secured in adjusted positions by means of a jamb nut 27. The piston 26 reciprocates in a cylinder 28 formed integrally with the casing 18 radially of the chamber 19, and having its end closed by a removable head 29. Approximately at the center of one side, the cylinder 28 has an inlet 30 which communicates directly with a port 31 and which is connected with a suitable source of steam or compressed air by means of a pipe shown at 32 in Figs. I and II. Adjacent its outer end and at the bottom, the cylinder 28 is furthermore provided with an outlet exhaust port 33 for exhaust of the motive fluid incident to the return strokes of the piston 26. Admission of the motive fluid into and its exhaust from the cylinder 28 is governed by a hollow cup-like valve 35 located within the cylinder 28 behind the piston 26. This valve 35 is directly actuated by the piston 26 through a screw 36 engaging axially into the rear end of the piston and having a head 36a, which, as the piston moves forward in the cylinder, engages the cross web 35a of said valve. During the return strokes of the piston 26, the valve 35 is shifted through contact of the rear face of said piston with the contiguous face of the valve. As shown, the valve 35 is

formed with an annular distributing groove 37 (see Fig. V) adapted for registry with the inlet port 31 of the cylinder, said groove being open to the interior of the cylinder through a number 5 of radial ports 38, and the cross web 35a at the end of the valve being provided with a series of openings 39 for access of the motive fluid to the rear face of the piston 26.

Slidably guided in an opening 40 in the casing 10 18 in direct line with, but opposite to the cylinder 28, is a thimble-like buffer stop 41 which is subject to a helical compression spring 42. As shown in Figs. II, III and V, this buffer stop 41 projects into the chamber 19 of the casing 18 so that its 15 rounded end may be engaged alternately by the curved edges 23a, 23b of the cam 23. Through this provision, the bell 10 is permitted to swing substantially through a full revolution in either direction but prevented from turning over completely, with attendant retardation thereof as it 20 nears the limits of its oscillations, and avoidance of shocks to the mechanism. The buffer stop 41 is accessible for inspection or replacement upon removal of a screw plug 43 which serves as an 25 abutment for the outer end of the spring 42.

The operation of our novel bell ringing mechanism is as follows: Assuming the parts to occupy the positions shown in Figs. II and III, upon admission of motive fluid into the cylinder 28 30 through the port 31 and the registering groove 37 and radial openings of the valve 35, the piston 26 is urged forward in said cylinder 28. Through cooperation of the ball 24 with the convex edge 23a of the cam 23 the bell 10 is swung 35 counter-clockwise. As the forward movement of the piston 26 continues, the head 36a of the screw 36 eventually encounters the cross-web 35a of the valve 35, so that the latter is carried along with the piston to close the inlet port 31 for the 40 motive fluid. This occurs when the piston 26 has completed approximately two-thirds of its forward movement, the piston being carried the remainder of the way solely by expansion of the entrained pressure medium. Under the moment 45 tum induced in the bell 10, the latter continues its swing after the ball 24 rides off the edge 23a of the cam 23 and onto the concentric portion 23c until the opposite edge 23b of said cam engages the buffer stop 41 as shown in full lines in Fig. V. 50 Due to the pressure of the spring 42 and the cooperation of the rounded end of the buffer 41 with the cam edge 23b, the swing of the bell is gradually retarded and finally completely checked, the parts coming to rest in the position 55 shown in Fig. V with the valve 35 advanced beyond the exhaust port 33 of the cylinder 28. The energy stored in the spring 32 by the action just described causes the buffer stop 41 to re-act upon the edge 23b of the cam 23, and in this way 60 assists in the initiation of the reverse swing of the bell in the opposite or clockwise direction. As the reverse swing continues, the edge 23a of the cam 23 eventually re-counters the ball 24 and causes the piston 26 to be moved rearward, 65 the valve 35 remaining stationary for a time to permit exhaust of the cylinder 28 through the port 33. Soon however, the piston 26 finally engages the valve 35 and pushes the latter back to cover the exhaust port 33 with restoration of the 70 parts to the starting position shown in Figs. II and III. During the latter part of the return movement of the piston 26 it will be readily understood from Fig. III that a portion of the motive fluid is trapped in the rear end of the cylinder 28 75 for cushioning purposes. Incident to the next

forward movement of the piston 26, the ball 24 coacts with the convex surface 23b of the cam 23 with communication to the bell 10 of an impulse whereby the clockwise swing initiated as above explained, is boosted until the cam edge 23a encounters the buffer 41 as shown in dot and dash lines in Fig. V. When this occurs the swing of the bell 10 is retarded and finally checked exactly as before. Repetitions of this cycle 80 obviously result in swinging of the bell 10 first in one direction and then in the other with a retarded movement at the end of each swing. Under the described method of operation, it is evident that the action of our bell ringing mechanism will be 85 smooth and regular in determining bell soundings at a comparatively moderate but uniform frequency. 90

Having thus described our invention, we claim:

1. Ringing mechanism for locomotive bells and the like comprising a rotary cam affixed to the swinging axis of the bell, said cam having a radial lobe with oppositely-sloped side edges; and a reciprocating actuating member coacting, during successive power strokes, alternately with the oppositely-sloped edges of the cam to impart 100 swinging movement to the bell first in one direction and then in the other. 95

2. Ringing mechanism for locomotive bells and the like comprising a rotary cam affixed to the swinging axis of the bell, said cam having a radial lobe with oppositely-sloped side edges; a reciprocating actuating member coacting, during successive power strokes, alternately with the oppositely-sloped edges of the cam to impart 105 swinging movement to the bell first in one direction and then in the other; and means to confine the bell to oscillatory movement. 110

3. Ringing mechanism for locomotive bells and the like comprising a rotary cam affixed to the swinging axis of the bell, said cam having a radial lobe with oppositely-sloped side edges; a reciprocating actuating member coacting, during successive power strokes, alternately with the oppositely-sloped edges of the cam to impart swinging movement of the bell first in one direction 115 and then in the other; and yielding means also coacting alternately with the oppositely-sloped edges of the cam to prevent complete rotations of the bell and to gradually retard the bell as it near the limits of its swings in opposite directions. 120

4. Ringing mechanism for locomotive bells and the like comprising a rotary cam affixed to the swinging axis of the bell, said cam having a radial lobe with oppositely-sloped side edges; a reciprocating actuating member coacting, during successive power strokes, alternately with the oppositely-sloped edges of the cam to impart swinging movement to the bell first in one direction and then in the other; and a spring-influenced 130 buffer stop also coacting alternately with the oppositely-sloped edges of the cam to prevent complete rotations of the bell and to gradually retard the bell as it approaches the limits of its 135 swings in opposite directions. 140

5. Ringing mechanism for locomotive bells and the like comprising a rotary cam affixed to the axis of the bell, said cam having a radial lobe with oppositely-sloped side edges; and a fluid actuated cylinder with a piston to coact, during successive power strokes, alternately with the oppositely-sloped edges of the cam to impart swinging movement to the bell first in one direction and then in the other. 145

6. Ringing mechanism for locomotive bells and 150

the like comprising a rotary cam affixed to the swinging axis of the bell, said cam having a radial lobe with oppositely-sloped side edges; a fluid actuated cylinder with the piston to coact, during successive power strokes, alternately with the oppositely-sloped edges of the cam to impart swinging motion to the bell first in one direction and then in the other; and automatically-actuated valve means for controlling admission and exhaust of motive fluid to and from the cylinder. 10

7. Ringing mechanism for locomotive bells and the like comprising a casing adapted for attachment to the supporting frame of the bell, said casing affording a circular chamber concentric with the axis of the bell, and a cylinder radial of said chamber; a rotary cam affixed to the axis of the bell within the circular chamber of the casing, said cam having a radial lobe with oppositely-sloped side edges; a piston within the cylinder coacting, during successive power strokes, alternately with the oppositely-sloped edges of the cam to impart swinging motion to the bell first in one direction and then in the other; and 15

20 valve means for controlling admission and exhaust of motive fluid to and from the cylinder.

valve means for controlling admission and exhaust of motive fluid to and from the cylinder.

8. Ringing mechanism for locomotive bells and the like comprising a casing affording a circular chamber concentric with the axis of the bell, a cylinder radial of said circular chamber, and a detachable cover plate closing the chamber at one side, said cover plate having a boss co-axial with the chamber adapted to be welded to the outer face of a bearing for the bell axis on a supporting frame; a rotary cam affixed to the axis of the bell within the circular chamber of the casing, said cam having a radial lobe with oppositely-sloped side edges; a piston within the cylinder coacting, during successive power strokes, alternately with the oppositely-sloped edges of the cam to impart swinging motion to the bell first in one direction and then the other; and automatically actuated valve means for controlling admission and exhaust of motive fluid to and from the cylinder. 80
